UNITED STATES PATENT OFFICE.

LOUIS DEJONGE, JR., OF NEW YORK, N. Y.

COLLAPSIBLE SCREEN.

No. 820,769.

Specification of Letters Patent.

Patented May 15, 1906.

Application filed December 9, 1905. Serial No. 291,099.

To all whom it may concern:

Be it known that I, LOUIS DEJONGE, Jr., a citizen of the United States, and a resident of the city of New York, Stapleton, borough of 5 Richmond, in the county of Richmond and State of New York, have invented a new and Improved Collapsible Screen, of which the following is a full, clear, and exact description.

10 The purpose of the invention is to provide a construction of screen whereby it can be rolled up, making a small package for storage or transportation, and whereby also it can be quickly, conveniently, and firmly set up for 15 use.

The invention consists of the novel construction and combination of the several parts, as will be hereinafter fully set forth, and pointed out in the claims.

20 Reference is to be had to the accompanying drawings, forming a part of this specification, in which similar characters of reference indicate corresponding parts in all the figures.

25 Figure 1 is a perspective view of the improved screen. Fig. 2 is an inner face view of a portion of the screen. Fig. 3 is an outer face view of that portion of the screen shown in Fig. 2, and Fig. 4 is a horizontal section 30 taken practically on the line 4-4 of Fig. 3.

The screen, as illustrated, comprises two panels A and B. The framework of each panel consists of two uprights 10 and 11 and upper and lower latch-bars 12 and 13, which bars are pivoted to one upright, and when the screen is set up the latch-bars engage 35 with buttons 14 or their equivalents upon the other upright.

In placing the latch-bars on the frame one 40 is pivoted to the outer upright of the frame and the other to the inner upright, so that when the frame is to be folded or rolled up a latch-bar can be carried over and parallel with each of the uprights.

45 The body 15 of the screen is made of canvas, fabric, or other pliable material and is tacked or otherwise secured to the uprights of both panels A and B. At the outer edge of each upright a molding or longitudinal bat- 50 ten 16 is secured, which moldings or battens serve to uniformly and firmly hold the ma- terial of the body to the uprights 10 and 11. The body material is continuous from the

outer upright of one panel to the outer edge of the mating panel, and being secured to the 55 outer longitudinal portions of the inner up- rights of the panels the said body in itself constitutes a hinged connection between the panels.

It is evident under the construction above 60 set forth that if the latch-bars 12 and 13 are disconnected from their buttons or keepers 14 and are carried down longitudinally of the uprights 10 and 11 the said uprights can be 65 rolled up in the body material, thereby pro- ducing a package practically circular in cross- section and of very small dimensions trans- versely. It is furthermore evident that the screen can be quickly and conveniently set up, as all that is needed is to unroll the body, 70 place the uprights vertically, and connect them by means of the latch-bars and buttons or keepers.

Having thus described my invention, I claim as new and desire to secure by Letters 75 Patent—

1. A screen comprising a plurality of panels, the frame of each panel comprising two uprights, a latch-bar pivoted to each up- 80 right, the latch-bar upon one upright being at the opposite end from the latch-bar upon the other upright, a keeper upon each upright for engagement by the latch-bar of the other upright and a body-section of pliable ma- 85 terial secured to the uprights, said body-sec- tion being continuous on all of the panels.

2. A screen comprising a plurality of panels, the frame of each panel comprising two uprights, a latch-bar pivoted to each up- 90 right, the latch-bar upon one upright being at the opposite end from the latch-bar upon the other upright, a keeper upon each upright for engagement by the latch-bar of the other upright and a body-section of pliable ma- 95 terial secured to the uprights, said body-sec- tion being continuous on all of the panels, and being secured to the uprights by battens ar- ranged longitudinally of the uprights.

In testimony whereof I have signed my name to this specification in the presence of 100 two subscribing witnesses.

LOUIS DEJONGE, JR.
